[57] **CLAIM**

The ornamental design for a handset, as shown and described.

DESCRIPTION

FIG. 1 is a perspective view showing the front and left side of my design for a handset;

FIG. 2 is a perspective view, similar to FIG. 1, showing the rear and left side thereof;

FIG. 3 is a front elevational view thereof;

FIG. 4 is a rear elevational view thereof;

FIG. 5 is a view taken from the left of FIG. 3;

FIG. 6 is a side elevational view taken from the right of FIG. 3;

FIG. 7 is a top plan view; and,

FIG. 8 is a bottom plan view.

The broken line showings of FIGS. 1–6 and 8 are for illustrative purposes only and form no part of the claimed design.

1 Claim, 8 Drawing Sheets

FIG. 1

FIG. 2

FIG. 3

FIG. 4

FIG. 5

FIG. 6

FIG. 7

FIG. 8
